UNITED STATES PATENT OFFICE.

GEORGE M. HUNTLEY, OF EVERETT, MASSACHUSETTS.

SUPPORTING STRUCTURE FOR DESKS, CHAIRS, &c.

1,156,232.

Specification of Letters Patent. Patented Oct. 12, 1915.

Application filed December 11, 1914. Serial No. 876,686.

To all whom it may concern:

Be it known that I, GEORGE M. HUNTLEY, a citizen of the United States, and resident of Everett, in the county of Middlesex and State of Massachusetts, have invented certain new and useful Improvements in Supporting Structures for Desks, Chairs, &c., of which the following is a specification.

This invention relates to furniture especially adapted for use in schools, libraries, etc., and is embodied in a supporting structure comprising a base adapted to be attached to a floor and a U-shaped supporting member including a neck secured to said base, and twin standards projecting upwardly from the neck at opposite sides of the base and having devices at their upper ends for attachment either to separate articles of furniture, such as a desk and a chair, or to a single article, such as an elongated desk or a table top.

The invention is also embodied in a construction of the base whereby the U-shaped supporting member may be rotatively adjusted to vary its angularity and enable a desk and a chair supported by the standards thereof to face in different directions.

Of the accompanying drawings forming a part of this specification: Figure 1 represents a side elevation of a supporting structure embodying my invention, the twin standards being used to support a desk and a chair; Fig. 2 represents a section on line 2—2 of Fig. 1; Fig. 3 represents a perspective view, showing the twin standards adapted to support two desks side by side, or a single elongated desk.

The same reference characters indicate the same or similar parts in all the views.

In the drawings I have shown the base constructed to permit the supporting member to be rotatively adjusted so that the angularity of the twin standards of the supporting member hereinafter described may be varied to permit said standards to stand in vertical planes having different angular relations to the center of rotation of the supporting member. Said base includes a bottom member 12, preferably of circular form, adapted to be attached by screws 13 or otherwise to a floor, said bottom member having in its upper side a circular recess forming a turn-table support.

The base also includes a top member composed of a turn table 14 adapted to rotate on said support and having a two-part

socket composed of a lower part or cradle 15 integral with the turn table and an upper part or cap 16 which is adjustable relatively to the cradle so that the socket may be compressed on a neck inserted in it. The parts of the base are connected by a king-bolt 17 inserted in holes formed for its reception in the bottom member 12, the turn table 14 and the socket portions 15 and 16, said bolt having a head 18 bearing on the under side of the bottom member and a nut 19 bearing on the upper side of the socket portion or cap 16.

20 and 21, 21, represent parts of a U-shaped supporting member, the part 20 being a horizontal neck extending through the base socket and apertured to receive the king-bolt 17, while the parts 21, 21, are twin standards projecting upwardly from opposite ends of the neck and at opposite sides of the base. As here shown said parts are lengths of tubing connected by elbows 22. The king-bolt passing through the neck 20 prevents an axial turning movement of the neck in the socket and therefore maintains the standards upright.

The twin standards are preferably of telescopic construction and include standard portions 21^a, adapted to slide in the standard portions 21 and adapted to be secured at various heights by set screws 23. The standard portions 21^a are provided at their upper ends with attaching devices, such as spiders 24, adapted to be secured by screws 25 to a furniture part or parts. As shown by Fig. 1, the twin standards are of different heights, the higher standard being adapted to support a desk 26 and the lower standard 27. As shown by Fig. 3, the standards are of equal height and adapted to support either two desks 26 located side by side, or, if desired, a single elongated desk such as would be formed by connecting the two desks. The twin standards, when of equal height, may obviously be used to support two chairs.

The embodiment of the invention shown by Fig. 1 is particularly useful in school rooms, the supporting structure carrying a desk, the user of which occupies a chair carried by another supporting structure not shown. The described construction of the base enables the structure to be rotatively adjusted to cause the desk and chair to face in any desired direction. While the twin standards are supported by the same base,

the construction is such that the jars imparted to the chair are not communicated to the accompanying desk.

The base is of such form that it may be readily cleaned by sweeping and offers no recesses for the lodgment of dirt.

The king-bolt passing through the bottom member 12, the cradle 15 and the neck 20, prevents the neck from turning and from 10 moving endwise and sidewise, while the nut 19 of said bolt and the cap 16 coöperate with the bolt in holding the neck firmly down on the cradle.

Having described my invention, I claim:

15 1. A supporting structure comprising a base adapted to be attached to a floor and provided with a socketed cradle, a U-shaped supporting member including a neck seated on the cradle and twin standards projecting

20 upwardly from the neck at opposite sides of the base, a king-bolt passing through the base and neck, and preventing rotative, endwise, and sidewise movements of the neck, and holding-down means coöperating with 25 said bolt in preventing upward movements of the neck.

2. A supporting structure comprising a base adapted to be attached to a floor and provided with a socketed cradle, a U-shaped 30 supporting member including a neck seated on the cradle and twin standards projecting upwardly from the neck at opposite sides

of the base, a cap bearing on said neck, and a king-bolt passing through the base, neck, and cap, and provided with a clamping nut 35 bearing on the cap.

3. A supporting structure comprising a base including a bottom member adapted to be attached to a floor, and formed to serve as a turn-table support, a turn table rotatively adjustable on said support and having a two-part socket, and a king-bolt extending through the bottom member, turn table and socket, and having means for compressing the socket and securing the turn 45 table and socket in any position to which they may be adjusted, and a U-shaped supporting member including a neck extending through said socket and aperture to receive the king-bolt, and twin standards projecting upwardly from the neck at opposite sides of the base and having attaching devices at their upper ends, the supporting member being rotatively adjustable with the turn table and socket, and secured by said 50 socket and bolt in any position to which it may be adjusted.

In testimony whereof I have affixed my signature, in presence of two witnesses.

GEORGE M. HUNTLEY.
